UNITED STATES PATENT OFFICE.

FRANK W. HOWARD AND HOWARD M. BROWN, OF NEW YORK, N. Y.

UMBRELLA-RUNNER.

1,268,353.

Specification of Letters Patent. Patented June 4, 1918.

Application filed September 17, 1914. Serial No. 862,161.

To all whom it may concern:

Be it known that we, FRANK W. HOWARD and HOWARD M. BROWN, citizens of the United States, residing at New York, in the county of New York and State of New York, respectively, have invented new and useful Improvements in Umbrella-Runners, of which the following is a specification.

This invention relates to umbrellas, and particularly to the runners of umbrellas. A principal object of the invention is to produce a runner of very simple construction which can be easily operated and which also can be very economically manufactured.

One of the objects of the invention is to produce a runner having means for locking the runner to the stick of the umbrella when the umbrella is in its open position.

The invention consists in the general combination of parts and features hereinafter described, all of which contribute to produce an efficient umbrella runner.

A preferred embodiment of our invention will be particularly described in the following specification while the broad scope of our invention will be pointed out in the appended claims.

In the drawings:—

Figure 1 is a side elevation showing a runner and contiguous parts.

Fig. 2 is a plan showing the runner without the stick and showing the stretchers attached thereto.

Fig. 3 is a vertical section through the runner shown in Fig. 1.

Fig. 4 is a cross section through this runner and showing the same in its locking position.

Fig. 5 is a side elevation of a locking member which constitutes a feature of the invention.

Fig. 6 is a side elevation showing a runner having another form of locking member.

Fig. 7 is a vertical section through the runner shown in Fig. 6.

Fig. 8 is a cross section through the runner shown in Fig. 6 and showing the same in its locking position.

Fig. 9 is a vertical section through the runner showing a modified form of locking member.

Figs. 10 and 11 are front and side elevations respectively, of the locking member.

Fig. 12 is a vertical section through the runner showing another form of locking member.

Fig. 13 is a side elevation of the locking member shown in Fig. 12.

Referring more particularly to the parts, 15, in Fig. 1, represents the stick of the umbrella upon which the runner 16 normally slides freely, said runner consisting preferably of a sleeve 17 having any suitable means such as a collar 18 at its upper end for attaching the same to the stretchers 19; 65 the sleeve 17 is preferably made with an oval shaped opening (see Fig. 2), the small dimension of the oval being substantially the same as that of the stick 15 which runs through the sleeve. 70

Between the stick and the sleeve 17, and unattached to the stick, I prefer to provide an elongated locking member 20. This locking member and the sleeve are arranged so that the sleeve holds the locking member 75 in position. That is, it retains it adjacent the stick. The locking member is constructed in such a way that it has a relative movement on the sleeve and operates so that when the locking member is in one position, as in Fig. 4, it jams the stick over against the end of the oval and clamps the sleeve to the stick. 80

This is preferably accomplished by forming the locking member with a stem which 85 extends longitudinally of the sleeve and this stem has different dimensions measured in different transverse or radial planes so that when rotated it will jam against the stick as suggested. This is preferably accomplished 90 by forming a bend 21 in the stem and it is evident that when the angle 22 of this bend is against the stick, or against the sleeve, the stick will be pressed over against one end of the oval. This locking member is preferably 95 made of resilient wire, and in order to retain it in the sleeve, I prefer to provide its upper end with an extension or hook 23 which projects over the upper end of the sleeve 17, and its lower end with an extension 24 which forms a handle. 100

We may form the locking member as indicated in Figs. 6, 7 and 8, that is, the stem of the locking member has a flattened extension 25 which is received in one end of the oval 105 of the sleeve 16, the upper end of the stem

being formed with a hook 27 which engages over the upper end of the sleeve and prevents the locking member from dropping out; the lower end of the locking member 5 preferably has an integral extension 28 forming a lever or finger piece for operating the locking member.

Or we may form the locking member in the form of a bow 29, see Figs. 9 to 11, the 10 upper end of the bow having a slight hook 30 to perform the same function as the hook 27. When the finger piece 31 of this locking member is rotated into position to hold the bow 29 in the position shown in Fig. 9, the 15 bow clamps the stick 32.

Instead of forming the locking member as a bow 29, we may give it the form of an ogee curve or wave 33, as shown in Fig. 12, the said curve being formed in a plane so 20 that the side view of the locking member presents the appearance shown in Fig. 13. The upper end of the locking member is preferably formed with a hook 34 which assists in retaining it in position, the lower 25 end being formed with an integral extension lever or finger piece 35.

It is understood that the embodiment of the invention described above is only one of many forms or embodiments the invention 30 may take and we do not wish to be limited in the practice of the invention nor in our claims to the particular embodiment described.

What we claim is:—

35 1. In an umbrella, in combination, a stick, a runner encircling the stick and comprising an oval sleeve, and means mounted on said sleeve to move about an axis extending longitudinally of said sleeve for jamming said

stick against said sleeve at one end of the 40 oval thereof.

2. In an umbrella, in combination, a stick, a runner encircling the stick and comprising an oval sleeve, and means movably mounted in said sleeve for jamming said stick against 45 said sleeve at one end of the oval thereof, said means comprising an elongated locking member extending longitudinally of said sleeve disposed in one end of the oval of said sleeve between the stick and the sleeve. 50

3. In an umbrella, the combination of a stick, a locking member lying loosely against the side of the stick and unattached to the stick, a runner having a substantially oval-shaped opening, the wall whereof encircles 55 the stick and the locking member, said runner operating to retain the locking member in the space at one end of the oval opening of the runner between the side of the stick and the wall of the runner, said locking member being rotatable on a longitudinal axis extending longitudinally of the stick, and having different dimensions in different radial planes from its axis of rotation, whereby it will jam the runner on the stick 60 in one position of the locking member and permit the free movement of the runner along the stick in another position of said locking member. 65

In testimony whereof we have hereunto 70 set our hands in presence of two subscribing witnesses.

FRANK W. HOWARD.
HOWARD M. BROWN.
